UNITED STATES PATENT OFFICE.

WILLIAM EUGENE BOURNE, OF LYONS, NEW YORK.

DESIGN FOR A PAPER-RECEPTACLE.

SPECIFICATION forming part of Design No. 23,449, dated July 10, 1894.

Application filed April 6, 1894. Serial No. 506,633. Term of patent 3½ years.

To all whom it may concern:

Be it known that I, WILLIAM EUGENE BOURNE, a citizen of the United States, residing at Lyons, county of Wayne, and State of New York, have invented and produced a new and original Design for Paper-Receptacles, of which the following is a specification, reference being had to the accompanying drawings, in which—

10 Figure 1, is a side view of the case, complete. Fig. 2, is a cross section thereof.

15 The leading feature of my design consists in a cylindrical body, the outlines of which, when viewed in elevation, fall within a rectangle and thus present to the eye a combined effect of smooth, symmetrical outline.

20 —A—is the body, circular, as shown in cross section in Fig. 2. The body, A, is provided, near its upper end with a series of annular ribs or beads, c, and a similar series of beads, d, is formed on said body near the lower end thereof.

—B—is the cover, its upper face convex, and having a beading —a—about its periphery said bead extending some distance beyond the sides of the body, A, of the case.

—b—is a supporting arm consisting of two members which extend parallel to the sides of the body, A, and are connected at their adjacent ends by a short horizontal arm which extends from the case, A, to a point beyond the bead on the cover, B.

What I claim is—

The design for a paper receptacle, substantially as herein shown and described. 35

In witness whereof I have hereunto set my hand this 3d day of April, 1894.

WILLIAM EUGENE BOURNE.

In presence of—

HENRY A. BERNS,
W. M. YOUNG.
